UNITED STATES PATENT OFFICE.

EDWIN HAVILAND, OF PLAINFIELD, NEW JERSEY.

DESIGN FOR TABLE-WARE.

SPECIFICATION forming part of Design No. 12,546, dated October 25, 1881.

Application filed April 1, 1881. Term of patent 7 years.

To all whom it may concern:

Be it known that I, EDWIN HAVILAND, of Plainfield, in the State of New Jersey, have invented a new and useful and ornamental Design for Table-Ware, of which the following is a description.

The drawings show my design as applied to a soup-tureen.

Figure 1 is a plan; Fig. 2, a side elevation, 10 and Fig. 3 an end elevation.

The general form of the vessel is a square or oblong square with projecting rounded corners, as shown in Fig. 1. On each side of each corner is an indentation, *a*, and the lines *b* connecting these indentations may be curved, as shown, or straight. The pieces consist of a foot and body joined together, and may be either covered or uncovered.

The outline of the design is clearly shown in 20 Figs. 2 and 3.

c d in Figs. 2 and 3 show the elevation of the foot, the base-line of which may be plain or indented, as shown at *e*.

e g show the outline of the body rising from 25 the foot. Ornamented bands in relief are so placed upon the dish and foot as to form panels and borders *h*.

The cover projects beyond the body, and rises toward the center in curved lines. It has 30 upon its upper surface raised bands forming panels and borders. The exterior lines of the cover conform to those of the dish in being

square, or an oblong-square, with rounded corners and indentations.

The handle on the cover consists of double 35 open bows joined at the ends, fastened upon the piece apparently by a band crossing the lower part of the handle transversely through the opening, with simulated clamps and bolt-heads upon the cover. Butterflies seem to be 40 emerging from under each end of the handle, the wings rising on each side and forming an ornament, as is shown in Figs. 2 and 3.

I make the handles upon the body to differ 45 from that of the cover by placing them perpendicularly and dividing the lower part, as thus placed, into two parts joined into one at the top, and separated below, as is shown in Fig. 3. The butterfly ornament is also here applied, but it may be omitted.

I claim—

1. The design for table-ware, substantially as shown in the drawings.

2. The design for handles for table-ware, substantially as shown in the drawings.

3. The outline design for the general shape, as shown in the plan view, Fig. 1.

In testimony that I claim the above design for table-ware I hereto affix my signature this 14th day of December, A. D. 1880.

EDWIN HAVILAND.
